US0D1027951S

(12) **United States Design Patent** (10) **Patent No.:** **US D1,027,951 S**
(45) **Date of Patent:** **** May 21, 2024**

(54) **GAME CONTROLLER**

(71) Applicant: **DONGGUAN IINE TECHNOLOGY CO., LTD**, Dongguan (CN)

(72) Inventors: **Zhongjie Zhang**, Dongguan (CN); **Xiancheng Tang**, Dongguan (CN)

(73) Assignee: **DONGGUAN IINE TECHNOLOGY CO., LTD**, Dongguan (CN)

(**) Term: **15 Years**

(21) Appl. No.: **29/729,461**

(22) Filed: **Mar. 26, 2020**

(30) **Foreign Application Priority Data**

Mar. 11, 2020 (CN) 202030079826.8

CLAIM

The ornamental design for a game controller, as shown and described.

DESCRIPTION

FIG. 1 is a perspective view of a game controller showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view of the game controller; and,

FIG. 8 is an enlarged bottom plan view thereof.

1 Claim, 8 Drawing Sheets
